UNITED STATES PATENT OFFICE.

WALTER J. VOLLRATH, OF SHEBOYGAN, WISCONSIN, AND MAX M. COHEN, OF CHICAGO, ILLINOIS, ASSIGNORS TO PORCELAIN ENAMELING ASSOCIATION OF AMERICA, OF SHEBOYGAN, WISCONSIN, A CORPORATION OF WISCONSIN.

RECEPTACLE-COVER.

1,153,586.

Specification of Letters Patent. Patented Sept. 14, 1915.

Application filed March 7, 1914. Serial No. 823,252.

To all whom it may concern:

Be it known that we, WALTER J. VOLLRATH and MAX M. COHEN, citizens of the United States, residing at Sheboygan, in the county of Sheboygan and State of Wisconsin, and at Chicago, in the county of Cook and State of Illinois, respectively, have invented a new and useful Receptacle-Cover, of which the following is a specification.

10 Our invention relates more particularly to receptacle-covers formed of sections of glass and metal, respectively, a condition presented particularly in coffee-percolators wherein it is desirable that the top of the 15 cover, which fits into the metal portion thereof, be transparent to permit the action of the percolator to be observed; and more especially to covers, the metal portions of which are of enameled wear.

20 While the glass top-portions of the covers may be caused to accurately fit the metal portions of the covers, where the latter are stampings, the desired fit of the glass portion of the cover cannot be obtained 25 uniformly where the metal portion of the cover is enameled, without requiring subsequent relatively expensive operations on the enameled portions of the covers.

Our primary object is to provide novel, 30 simple and inexpensive means for securing the glass portions of covers in place on the metal portions thereof, and more particularly where the metal portions are enameled.

Referring to the accompanying drawing 35 Figure 1 shows by a view in broken sectional elevation the upper portion of a coffee-percolator, the cover of which is constructed in accordance with our invention, the section being taken at the line 1 on Fig. 40 2. Fig. 2 is a bottom plan view of the inside of the cover shown in Fig. 1. Fig. 3 is a section taken at the line 3 on Fig. 2, and viewed in the direction of the arrow. Fig. 4 is a broken plan view of the metal section 45 of the cover, and Fig. 5, a face view of a contractile and expansible ring which we prefer to employ as the securing means for the glass section of the cover; this ring being shown expanded, and the inner lower 50 end of the said glass section being shown by dotted lines, this view representing the relation of the ring to the top cover upon expanding the ring to apply it to, or remove it from, said top section.

We have shown our invention as applied 55 to a cover for a coffee-percolator, wherein the cover is represented at 6. This cover, in accordance with common practice, is formed of a section 7 of metal, enameled in the construction illustrated, and a hollow- 60 top section 8 of glass. The cover-section 8, at its lower end, is of circular shape in cross-section, and carries a flange 9, this cover-section extending into the cover-section 7 through an opening 10 in the latter, and 65 seating thereon at the flange 9. The opening 10 is preferably slightly larger than the diameter of the lower end of the cover-section 8 and preferably contains recesses 11 in its walls with which lugs 12 on the 70 cover-section 8 are adapted to register upon the act of assembling together the cover-sections 7 and 8 as stated.

For the purpose of preventing accidental separation of these cover-sections, we provide 75 retaining means coöperating therewith, which preferably are in the form shown and comprise an expansible and contractible ring 13 adapted to be applied to the portion of the cover-section 8 which extends into the 80 cover-section 7, as stated, this ring preferably encircling the inner end of the cover-section 8 between the lugs 12 and the marginal edge of the opening 10 and thus preventing displacement of the section 8. The 85 ring 13 is preferably so formed as to grip the section 8, it being preferably formed of spring wire with overlapping ends 14 having deflected portions 15, shown as of eye-form, forming finger grips, whereby the 90 ring 13 may be readily expanded, against its inherent elasticity, by drawing the portions 15 toward each other, for application to, or withdrawal, from the cover-section, as represented in Fig. 5. 95

It will be readily understood from the foregoing, that by the use of our invention, the opening 10 in the section 7 may be made of such diameter as to permit the glass section 8 to readily expand relative to the 100 metal section 7, and that care need not be exercised in the application of the enamel about the opening 10.

While we have illustrated and described a particular embodiment of our invention, 105 we do not wish to be understood as intending to limit it thereto, as the same may be variously modified and altered without de-

parting from the spirit of our invention; it being our intention to claim our invention as fully and completely as the prior state of the art will permit.

5. What we claim as new and desire to secure by Letters Patent is—

1. A removable cover for closing an opening in a receptacle, comprising a metal section, having a central opening and a glass dome extending into and through said opening, and a spring ring coacting with the inner end of the dome and adjacent surface of said metal section for holding the parts of the cover together.

15. 2. A removable cover for closing an opening in a receptacle, comprising a metal section, having a central opening and a glass dome extending into and through said opening, said parts having coacting recesses and lugs adapted to register as the parts are as-

sembled, and a spring ring coacting with the inner end of the dome and adjacent surface of said metal section for holding the parts of the cover together.

3. A removable cover for closing an opening in a receptacle, comprising a metal section, having a central opening and a glass dome extending into and through said opening, said parts having coacting recesses and lugs adapted to register as the parts are 30 assembled, and spring means engaging the lugs on one part and coacting with the adjacent surface of the other part adapted to hold said parts of the cover together.

WALTER J. VOLLRATH.
MAX M. COHEN.
